VOLUME BOOSTER FOR WATER SYSTEMS

Carl Oscar Carlson, Oakland, Calif., assignor of one-half to Arthur Johnson, Berkeley, Calif.

Application August 29, 1955, Serial No. 531,136

6 Claims. (Cl. 4—26)

My invention relates to water systems and more particularly to a volume booster for such systems.

This application is a continuation-in-part of my application for Flushing System—Serial No. 333,503—filed January 29, 1953, now abandoned.

The invention is particularly adapted for use in homes and other places where direct pressure flush valves are not practical due to the small diameter water pipe customarily employed, which while of ample size for other uses, would not pass sufficient volume at a rate necessary to adequately flush a closet bowl.

Among the objects of my invention are,

- (1) To provide a novel and improved volume booster for a water system;
- (2) To provide a novel and improved volume booster for a water system, which is of simple construction and may be economically produced;
- (3) To provide a novel and improved volume booster for a water system, which functions efficiently at all times;
- (4) To provide a novel and improved volume booster for a water system, which may be altered to satisfy different demands, merely through the inter-changing of tanks of different capacities.

Additional objects of my invention will be brought out in the following description of a preferred embodiment of the same, taken in conjunction with the accompanying drawings wherein;

Figure 1 is a diagram of a portion of a water system supplying a gang of toilets and incorporating in section, the volume booster of the present invention;

Figure 2 is an enlarged view in section, of the air intake valve assembly of Figure 1; and

Figure 3 is a view taken in the plane 3—3 of Figure 1.

Referring to the drawings for details of my invention in its preferred form, the same is shown incorporated in a water system involving a pipe 1 of small diameter through which it is desired to supply the water for flushing a gang of toilets 3 coupled to a manifold 5 through branch pipe connections 7, all of sufficiently large diameter to carry the volume of water necessary to flush the toilets. Each of the branch pipe connections includes a flush valve 8 of a conventional type.

In the supply pipe, as is the custom, a check valve 9 is included, to prevent any possibility of reverse flow in this portion of the system, and thereby protect the rest of the system from possible contamination.

The volume booster 10 is connected into the system between the supply pipe 1 and the manifold pipe 5, and involves a closed storage tank 11 having a discharge coupling 13 of greater diameter than the supply pipe and sufficient to pass the required volume of water for flushing all toilets simultaneously. The discharge coupling is connected to the manifold, which places the tank in direct connection therewith.

Within the coupling is mounted a jet 15 with its input end 17 exposed for connection thereto, of the supply pipe 1. The jet terminates at its free end 19, within the dis-

2

charge end of the coupling, which accordingly places the supply pipe in direct communication with the manifold; and with flow through the manifold blocked off by the flush valves 8, the jet also places the supply pipe in flow connection with the storage tank. Accordingly, during such intervals when no flushing takes place, water will flow into the supply tank to a level 21 where the resulting air cushion 23 builds up to a pressure equaling that in the supply pipe.

10 Built into the tank is an air intake valve means 24 including a tube 25 mounted at one end, in a wall 26 of the tank, and terminating at its free end, substantially below such water level, as was previously indicated would be reached in the tank during quiescent conditions in the system. To this free end of the tube is mounted a valve assembly affixed to the end of the tube and involving a valve housing 29, while within the housing adjacent the tube, a valve seat 31 is provided for co-operation with a float valve 33 disposed in the housing and adapted normally to engage the valve seat when submerged in water.

The opposite end of the valve housing is preferably partially open, but provides a spring seat for a light spring 35 of the compression type adapted to engage the float valve and assist the same in the direction of seating and lightly hold the valve seated in the absence of water, but adapted to permit the retraction of the float valve when the pressure within the tank falls to a point below atmospheric pressure.

30 The volume of the tank in relationship to the number of toilets connected in the system, should be as much as to just about carry sufficient water to flush all such toilets simultaneously.

The operation of any flush valve will immediately initiate a combined flow of water from the supply pipe and tank for flushing purposes. As the water flows from the tank, the air cushion space naturally becomes larger and the pressure of the air cushion gradually diminishes until it drops to a value just below atmospheric pressure, which in the absence of other factors, would preclude further discharge of water from the tank, and thereafter diminish the flow to the closet bowl to that supplied by the water pipe alone. Under such conditions, an abnormally large tank would be required to satisfy the necessary flushing requirements for such system.

45 The presence of the jet, however, avoids the necessity for an abnormally large tank and permits of a tank of smaller volume, this by reason of the fact that a region of reduced pressure is developed about the jet; thus not only creating a greater differential pressure on the column 50 of water in the tank, to thereby increase the flow rate, but also permitting an additional volume of water to flow from the tank until a still lower sub-atmospheric pressure is reached within the air cushion space.

55 The degree to which the level will drop through the use of a jet, will depend of course on the degree to which the pressure about the jet is reduced. I have discovered that by departing from the conventional type of jet having a circular discharge opening, and restricting the same in one direction by squeezing, to bring about a resulting narrow elongating discharge opening 37, a considerably greater reduction in pressure around the jet can be realized than would be possible under otherwise identical conditions, even to the extent in one installation, of completely emptying the storage tank.

60 Any leakage or loss of air from the air cushion in the storage tank will alter operating conditions in the direction of reducing the amount of water capable of being discharged from the tank. The air intake valve assembly has for its function, to cure such a condition when it develops, and accordingly when the pressure in the space above the water drops to the sub-atmospheric value at which the valve is set to open, air will be per-

mitted to enter the storage tank and replenish the air above the water level to restore conditions to normal.

More effective intake of air is permitted by the provision of side openings 39 in the valve housing at locations just below the valve seat.

In lieu of the submerged air valve assembly described above, an air intake valve might be installed directly in the wall of the tank above the normal water level. The submersion of the valve assembly in the water, however, has for its purpose to prevent the drying or shrinking of any of the components, whereby to maintain the effectiveness of the valve and otherwise keep the valve components clean and free of dust or the like, and in this respect offers decided advantages.

From the foregoing description of my invention in its preferred form, it will be apparent that the same fulfills all the objects thereof, and that to accommodate the invention to satisfy different requirements, all that is necessary is to interchange an existing tank for one of sufficient capacity.

The invention illustrated and described is subject to alteration and modification without departing from the underlying principles involved, and I accordingly do not desire to be limited in my protection to such details as I have illustrated and described except as may be necessitated by the appended claims.

I claim:

1. A volume booster for a water system involving a supply line of diameter insufficient to adequately supply, in a direct manner, the requirements of a fixture supplied by said system, said booster comprising a closed storage tank having a discharge coupling of greater diameter than such supply pipe, for placing said tank in flow connection with such fixture, a jet mounted in said coupling with its input end exposed for connection thereto of such supply line and its discharge end restricted in one dimension only and terminating in substantially the plane of the discharge end of said coupling, said jet providing an inlet connection to said tank when said tank is thus connected in said water system, and air intake valve means for said tank.

2. A volume booster for a water system involving a supply line of diameter insufficient to adequately supply, in a direct manner, the requirements of a fixture supplied by said system, said booster comprising a closed storage tank having a discharge coupling of greater diameter than such supply pipe, for placing said tank in flow connection with such fixture, a jet mounted in said coupling with its input end exposed for connection thereto of such supply line, said jet providing an inlet connection to said tank when said tank is thus connected in said water system, and air intake valve means for said tank, said air intake valve means including a tube mounted at one end in a wall of said tank and terminating at its free end, within said tank and below normal water level reached in said tank during quiescent conditions in said system when connected therein, a valve assembly mounted at the free end of said tube, said assembly being submerged in water during use and involving a valve housing affixed to said tube, a valve seat within said housing, a valve in said housing adapted to normally engage said valve seat, said valve housing having at least one air escape opening at a point below said valve seat.

3. A volume booster for a water system involving a supply line of diameter insufficient to adequately supply, in a direct manner, the requirements of a fixture supplied by said system, said booster comprising a closed storage tank having a discharge coupling of greater diameter than such supply pipe, for placing said tank in flow connection with such fixture, a jet mounted in said coupling with its input end exposed for connection thereto of such supply line, said jet providing an inlet connection to said tank when said tank is thus connected in said water system, and air intake valve means for said tank, said air intake valve means including a tube mounted at one

end in a wall of said tank and terminating at its free end, within said tank and below normal water level reached in said tank during quiescent conditions in said system when connected therein, a valve assembly mounted at the free end of said tube, said assembly being submerged in water during use and involving a valve housing affixed to said tube, a valve seat within said housing adjacent the end of said tube, a float valve in said housing adapted to normally engage said valve seat when submerged in water, said valve housing having at least one air escape opening therethrough at a point below said valve seat, and spring means lightly holding said float valve in position in the absence of water.

4. A volume booster for a water system involving a supply line of diameter insufficient to adequately supply, in a direct manner, the requirements of a fixture supplied by said system, said booster comprising a closed storage tank having a discharge coupling of greater diameter than such supply pipe, for placing said tank in flow connection with such fixture, a jet mounted in said coupling with its input end exposed for connection thereto of such supply line and its discharge end terminating in substantially the plane of the discharge end of said coupling, said jet providing an inlet connection to said tank when said tank is thus connected in said water system, and air intake valve means for said tank, said air intake valve means including a tube mounted at one end in a wall of said tank and terminating at its free end, within said tank and below normal water level reached in said tank during quiescent conditions in said system when connected therein, a valve assembly mounted at the free end of said tube, said assembly being submerged in water during use and involving a valve housing affixed to said tube, a valve seat within said housing, and a valve in said housing adapted to normally engage said valve seat, said valve housing having at least one air escape opening at a point below said valve seat.

5. A volume booster for a water system involving a supply line of diameter insufficient to adequately supply, in a direct manner, the requirements of a fixture supplied by said system, said booster comprising a closed storage tank having a discharge coupling of greater diameter than such supply pipe, for placing said tank in flow connection with such fixture, a jet mounted in said coupling with its input end exposed for connection thereto of such supply line and its discharge end restricted in one dimension, said jet providing an inlet connection to said tank when said tank is thus connected in said water system, and air intake valve means including a tube mounted at one end in a wall of said tank and terminating at its free end, within said tank and below normal water level reached in said tank during quiescent conditions in said system when connected therein, and a valve assembly mounted at the free end of said tube, said assembly being submerged in water during use and involving a valve housing affixed to said tube, a valve seat within said housing, and a float valve in said housing adapted to normally engage said valve seat when submerged in water, said valve housing having at least one air escape opening at a point below said valve seat.

6. A volume booster for a water system involving a supply line of diameter insufficient to adequately supply, in a direct manner, the requirements of a fixture supplied by said system, said booster comprising a closed storage tank having a discharge coupling of greater diameter than such supply line, for placing said tank in flow connection with such fixture, a jet mounted in said coupling with its input end exposed for connection thereto of such supply line and its discharge end restricted in one dimension and terminating in substantially the plane of the discharge end of said coupling, said jet providing an inlet connection to said tank when said tank is thus connected in said water system, and air intake valve means for said tank, said air intake valve means including a tube mounted at one end in the top wall of said tank and

extending down into said tank to a point below normal water level reached in said tank during quiescent conditions in said system when connected thereto, and a valve assembly mounted at the free end of said tube, said assembly being submerged in water during use and involving a valve housing affixed to said tube, a valve seat within said housing adjacent the end of said tube, a float valve in said housing adapted to normally engage said valve seat when submerged in water, said valve housing having at least one air escape opening at a point below 10 said valve seat, and spring means lightly holding said float valve in seating position in the absence of water.
